UNITED STATES PATENT OFFICE.

ARTHUR S. EVERETT, OF LAWRENCE, MASSACHUSETTS, ASSIGNOR TO PAGE MACHINE CO., INC., OF HAVERHILL, MASSACHUSETTS, A CORPORATION OF MASSACHUSETTS.

HEEL-BUILDING MACHINE.

Application filed January 27, 1917, Serial No. 144,883. Renewed April 2, 1921. Serial No. 458,086.

To all whom it may concern:

Be it known that I, ARTHUR S. EVERETT, a citizen of the United States, residing at Lawrence, in the county of Essex and State 5 of Massachusetts, have invented an Improvement in Heel-Building Machines, of which the following is a specification.

This invention relates to certain improvements in that type of machine known as the

10 "Page heel-building machine," in a commercial form of which the freshly-cemented lifts are assembled in a heel-form, and the heels thus formed, are then successively delivered thereby to a series of presses connected together in the form of an endless chain, so that they are pressed together immediately after being assembled, and are held pressed together for a sufficient time to enable the cement to set.

20 While the necessity of the employment of building nails is thus avoided, it has been found that building nails are desirable in some instances, particularly where a high heel, composed of pulp, is being manufactured; on account of the fact that the pulp is not so strong as the cement which holds the lifts together, so that, when the heel is pricked, in connection with the heel-attaching operation, the lifts sometimes split.

30 In a type of said machine in which the heel is built in a form which is adapted to open, against the action of springs, to permit the form to be withdrawn from the heel when clamped, there is a tendency to cause 35 the lifts to slip out of position to a slight extent, as they are clamped, which tendency is not sufficiently resisted by said springs of the light tension which it is necessary to employ, so that the heel produced is not always 40 as nearly perfect, under such conditions, as is usually desired.

An object of the invention is to provide means whereby a building nail may be driven in the heel as soon as it is assembled, 45 and before it is delivered to one of the presses, above referred to, so that all the advantages of having immediate pressure applied to the assembled lifts are secured, and, at the same time, the heel is provided with 50 a building nail, without serious delay to the building operation, as usually performed with the machine above referred to.

A further object of the invention is to provide means whereby the heel form may be 55 securely locked and the heel and lifts held

in desired position while the pressure is applied thereto, and to provide means whereby the form will be automatically unlocked to permit ready withdrawal of the form from the heel, after it has been clamped.

Other objects of my invention are to provide an improved form of building nail-driving mechanism, which is especially adapted for use in the connection above referred to.

I accomplish these objects by the means shown in the accompanying drawings, in which only such portions of the whole machine are shown as relate to the subject matter of the invention.

In the drawings;

Fig. 1 is a front elevation of a portion of a heel-building machine embodying the invention.

Fig. 2 is a transverse sectional view taken 75 at the line 2—2 of Fig. 1.

Fig. 3 is a transverse, detail, sectional view of the heel-clamping and nail-driving mechanism.

Figs. 4 and 5 are plan views of the portion 80 of the machine shown in Fig. 1, showing the parts in a different position.

Fig. 6 is a detail view of the form-locking mechanism.

Fig. 7 is a detail view of one of the heel-forming members.

In the drawing, 4 indicates a portion of the frame of the machine in which the guideways for the endless chain of heel-presses are formed, each of said presses comprising a 90 plate 5 in which a vertically movable rod 6 is mounted, said rod bearing an arm 7, supporting a clamping plate 8, for clamping a heel on the plate 5, and said rod 6 being sustained in inoperative position by the 95 roller 9, which is in turn supported by a vertically movable track-section 10, normally sustained by a light spring 11 and locked in raised position by a latch 12, mounted on a pivot 13, a strong spring 14 being arranged 100 to overcome the spring 11 and force said rod 6 downwardly to clamp a heel, when the latch 12 is disengaged from the track-section 10.

A horizontal table 16 is provided at the level at which the plates 5 travel, so that each plate is successively held in such a position that a heel may be formed on the table, and slid therefrom onto the plate. Said table 16 is provided with a pair of guideway ribs 18, in which a heel-form is 110

mounted to slide, said heel-form comprising a flat base-plate 20, having a pair of arms 22 at its longitudinal edges, which extend over said table. A T-shaped bracket 24 is mounted for forward and rearward adjustment on said base-plate 20, and a pair of heel-engaging fingers 26 are mounted in the arms of said bracket 24, respectively, said arms being arranged to extend divergently 10 rearward, and said fingers being flat and having their longitudinal edges formed to fit the rear end of a heel from top to bottom, and being supported by bolts 27, which pass perpendicularly through said bracket arms, 15 so that said fingers extend convergently and are adapted to be set, so that their lift-engaging edges incline toward each other from bottom to top, such adjustment being particularly desirable when high heels, which 20 taper considerably from base to top, are to be built.

A pair of heel-forming fingers 28 are pivoted on the rear end of each arm 22, in position to engage the breast end of a heel, and coil springs 30 are preferably provided which normally act to hold said fingers against stop shoulders in forming position, but are adapted to yield readily to permit said fingers to swing rearwardly, so that 25 the form may be withdrawn from a heel. Each pair of fingers 28 has a lug 32, which is arranged to extend oppositely thereto, with relation to the pivots thereof, beyond the outer sides of said arms 22, and a pair 30 of abutment rods 34 are mounted in the ribs 18, of the table 16, in position to engage said lugs 32, when the form is in lift-receiving position, buffer springs 35 being provided between the opposite ends of said rods 35 to those which engage said lugs, and adjusting screws 36, which are adapted to vary the tension of said springs.

A latch 40, outwardly pressed by a spring 41, is arranged in the form plate 20, in position to engage the outer end of a rigid bracket 42, mounted on the right hand rib 18, to lock the form in its outermost position against inward movement, and an operating lever 44, having an upright handle 45 thereon, is pivoted on a vertical pin 46 in the plate 20 and has a toe 48 arranged to engage a shoulder on the latch 40, so that, when said lever is swung rearwardly, it will cause the latch 40 to be disengaged 50 from the bracket 42.

A rod 50 is secured in the table 16 and has a stop-lug 52 threaded thereon and adapted to provide a positive stop for the form plate at the point at which the latch 55 40 engages its shoulder on bracket 42, to lock the form against inward movement.

A rod 54 is mounted to slide vertically in suitable lugs or brackets on the machine frame and a bell-crank lever is swiveled on 60 the upper end thereof, one arm 55 of which

has a handle at its end, and the other arm 56 of which has a vertical rod 57 adjustably mounted therein and having a clamping plate 58 on its lower end, the arrangement being such that said plate 58 may be carried to and from a position to clamp a pile of lifts held in position by the heel-forming members 26 and 28. A spring 60 is arranged on the rod 54 between a lug 59 on the frame and a collar 61 on the rod and acts normally to sustain said rod in a position to hold the clamping plate 58 at a suitable distance above the form, a stop nut 54' threaded on the lower end of said rod 54 being arranged to engage a guide lug 59' and limit the upward movement thereof. 75 80

A vertically disposed driver rod 62 is arranged to reciprocate in a guide tube 63 secured at its upper end to the table 16 and depending therefrom, said rod 62 having a small bore in its upper end to receive a driver 64 and the bore in the upper end of tube 63 being of corresponding diameter to provide a suitable guide therefor. A bracket 3 is mounted on the frame, and a sleeve 65 90 is arranged to slide therein, and has a spring 66 thereon between said bracket and an adjustable nut 67 on its lower end. A head 65' is formed on the upper end of said sleeve 65, providing a shoulder which limits the 95 downward movement thereof. The rod 62 is threaded in said sleeve 65 to permit vertical adjustment of the rod 62 therein, thereby to vary the initial position of the driver according to the length of the nail to be 100 driven.

A bifurcated operating lever 70 is arranged astride both the rods 62 and 54 and is connected, at an intermediate point, by links 72 to the head 65' of sleeve 65, and 105 at one end, by a pivot 73, to the rod 54. The opposite end of the lever 70 is connected to a treadle 74 by a chain or cable 76, which passes over a roll 77.

Any suitable means for causing the form, 110 by its inward movement, to move the latch 12 out of operative position may be provided, the means shown comprising a yoke 80, which is connected to the latch 12 and extends about the rod 10, and a slide 82 115 which is pivoted to said yoke and extends about the tube 63 and has its end in position to be engaged by a depending arm 84 on the form base plate 20, when the latter is pushed back to its rearmost position. An 120 operating lever 86, for the carrier driving mechanism, is also arranged to be engaged by the form on its return movement, as in 125 said prior machines.

The manner in which the heel-building 125 operation is performed with the above-described mechanism is as follows:—

The form base plate 20 is drawn out against the stop-lug 52 in which position it is locked by the latch 40, the forming mem- 130

bers 28 being thus held firmly in forming position by the engagement of the lugs 32 thereon with the ends of the rods 34. The lever arms 55 and 56 are swung to a position in which the clamp 58 is held at one side of the form. A suitable building nail is placed head down, so that it rests on the driver 64, as shown in Fig. 2, and then the cemented lifts are placed in the form, in the usual manner, until the heel is built to the required height. The clamping plate 58 is then swung into position over the heel and the treadle 74 is depressed causing the end of the operating lever 70 connected thereto, to be lifted. The tension of the spring 60, on rod 54, is made substantially less than that of the spring 66, so that, during the first part of this movement, the lever 70 will swing on the links 72 as a fulcrum, causing the rod 54 to be drawn downward until the plate 58 is forced into engagement with the pile of assembled lifts. As soon as the resistance to the plate 58 against the lifts exceeds the resistance of spring 66, then the fulcrum of the lever will be transferred to the pivot 73, (the lever thus being changed from one of the first class to one of the second class) and the sleeve 65 will be lifted, lifting the driver holder 62 and causing, by continued movement, the building nail to be driven through the heel, and clinched against the plate 58, which latter resists the force of the driving movement. The treadle is then released, so that the heel-clamping and nail-driving parts return to their normal positions. It will be noted that, during the entire clamping operation, the pile of lifts will be securely held in heel-form and will not be permitted to slip out of position.

The operator then pushes rearwardly on the handle 48, causing the lever 44 to be swung in this direction to a limited extent. This movement causes the withdrawal of the latch 40, so that it becomes disengaged from the bracket 42, and, as further movement of the lever, beyond what is necessary to release the latch, is prevented by a suitable stop, further inward pressure on the handle 48 is entirely effective to cause the form plate to be slid inwardly, so that the heel, which has just been assembled, and provided with a building nail, will be slid along on the table 16 onto one of the plates 5 beneath the clamp 8, and, when this point is reached, the arm 84 will move the slide 82 and trip the latch 12, so that the clamp will be released and the heel clamped on the plate.

When the form carries the lugs 32 away from the ends of rods 34, the breast-engaging members of the form will be unlocked, so that they will be merely held in position by springs 30. It will be apparent, therefore, that when the heel has been

clamped by one of the presses and the form is drawn back to build a new heel, the form members will yield and readily become disengaged from the clamped heel, as shown in Fig. 5, so that the return of the form 70 may be accomplished without delay, and, as the form reaches its outermost position, the lugs 32 will re-engage the rods 34, which latter, through the action of the springs 35, serve as buffers, as well as a part of the locking means for the form members. The form will be automatically relocked when the latch is in position to reengage the bracket 42, so that the above-described operation may be repeated. 80

I claim:—

1. In a heel-building machine, a heel press, a heel form reciprocally movable between a lift-assembling position and a position in which it delivers an assembled heel to said press and having a forming member movable to permit disengagement thereof from the heel as it is withdrawn from said press, means to lock said member in forming position while the form is in said lift-assembling position, and means to unlock said member when the form is moved from said position to permit disengagement of the form from the heel while held by said press. 90

2. In a heel-building machine, a heel-form movable between a lift-assembling position and a heel-delivering position and having a forming member movable to permit disengagement from a heel therein when withdrawn from said delivering position, an abutment arranged to be engaged by said forming member to force the latter into forming position, as the form is moved to assembling position, and means to lock the 105 form in said assembling position.

3. In a heel-building machine, a heel-form movable between a lift-assembling position and a heel-delivering position and having a forming member movable to permit disengagement from a heel therein when withdrawn from said delivering position, an abutment arranged to be engaged by said forming member to cause the latter to be forced into forming position as the form is moved into assembling position, a latch for automatically locking the form in said position, and an operating device movable successively to unlock the form and then move it to said delivering position. 110

4. In a heel-building machine, a heel-form movable between a lift-assembling position and a heel-delivering position and having a side section pivotally mounted to swing away from a heel therein, to permit withdrawal of the form from the heel when in delivering position, an abutment arranged to be engaged by said side section, as the form is moved into assembling position, to hold said side section in its nor- 125 130

mal position, a latch for automatically locking said form in said lift-assembling position, and means arranged to release said latch and move the form to delivering position.

5. In a heel-building machine, a heel-press, a heel-form reciprocally movable between a lift-assembling position and a position in which it delivers an assembled heel.

10 to said press, and having a forming-member movable to permit disengagement from the heel as it is withdrawn from said press, means to lock said member in forming position when the form is in said lift-assembling position, and means to clamp the lifts in the form temporarily while in said position.

6. In a heel-building machine, a heel-form reciprocally movable between a lift-assembling position and a heel-delivering position, means for pressing the lifts together and driving a building-nail therethrough while held by said form in said assembling position, a series of heel-presses successively movable into said delivering position to clamp a heel held in said form and means permitting said form to open to permit withdrawal thereof from a heel while held by one of said heel-presses.

7. In a heel-building machine, a heel-form movable between a lift-assembling position and a heel-delivering position and having a side section pivotally mounted to swing away from a heel therein, to permit withdrawal of the form from the heel when in delivering position, means to lock said side-section in normal position, when the form is in said assembling position, means to press the lifts into the form and drive a building nail therethrough when the side section is in locked position, and means to unlock the side section as the form is moved to delivering position.

8. In a heel-building machine, a heel-form movable to carry a heel held thereby from a lift-assembling position to a heel-delivering position, and having a yieldable side-member to permit delivery of the heel therefrom, a series of heel-presses successively movable into said delivering position to receive the heels from said form, clamping and nail-driving means arranged to press the lifts into said form and to drive a building-nail therethrough when in said assembling position, and means to lock said yieldable side-member in forming position when the form is in said assembling position, and to unlock the same when moved from said position to permit withdrawal of the form from the heel while held by one of said heel-presses.

9. In a heel-building machine, a heel-form reciprocally movable between a lift-assembling position and a heel-delivering position and having a movable side-member, means to lock said side-member in forming

position when the form is in assembling position, and to unlock the same as the form is moved from said position, means successively to press the lifts into said form and drive a building-nail therethrough when the form is in assembling position, and a series of heel-presses successively movable into position to clamp a heel held by said form in said delivering position.

10. In a heel-building machine, a heel-form reciprocally movable between a lift-assembling position and a heel-delivering position, and having a side-member pivotally mounted to swing laterally between a heel-forming position and a position permitting disengagement of the form from the heel, a lug projecting from said member oppositely thereto with relation to its pivot, a stationary abutment arranged to be engaged by said lug, as the form is moved into assembling position, to cause said side member to be forced into forming position, an automatic latch arranged to lock said form against movement when the form is moved into assembling position and hold said lug in engagement with said abutment, and an operating device movable successively to move said latch to unlock said form and to move the form to said delivering position.

11. In a heel-building machine, a table having guideways, a heel form reciprocally movable therein between a lift-assembling position and a heel-delivering position, said form having a heel-forming member pivoted thereon to swing horizontally to permit disengagement of the form from a heel when withdrawn from said delivering position, a lug on said forming-member extending oppositely with relation to the pivot thereof, an abutment on the table arranged to engage said lug and hold said member in forming position when said form is in assembling position, a spring-latch on said form arranged automatically to engage the table when the form is in assembling position, to lock the same in said position, a lever on the form movable in a direction to disengage the latch from the table and movable in the same direction to push the form towards delivering position, and means for forcing the lifts into the form when the latter is in assembling position.

12. In a heel-building machine, a horizontally disposed heel-form open at the top, a head vertically movable into said form to press the lifts against the bottom thereof, a driver bar arranged to move vertically beneath the bottom of the form to force a nail upwardly therein, a lever pivotally connected to said head and to said driver bar at different longitudinal points, springs arranged respectively to resist operative movement of said head and said driver bar, the tension of the spring for resisting movement of the head being less than that of the

other spring, and means to operate said lever to cause swinging movement thereof on said pivotal connections, successively.

13. In a heel-building machine a heel press, a heel form reciprocably movable between a lift-assembling position and a position in which it delivers an assembled heel to said press and having a forming member movable to permit disengagement thereof from the heel as it is withdrawn from said press, means for locking said member in forming position, while the form is in lift-assembling position, means for driving a building nail into the assembled lifts while said member is locked, and means thereafter to unlock said member to permit disengagement of the form from the heel while held by said press.
14. In a heel-building machine a series of heel presses successively movable to a heel receiving position, a heel form arranged at one side of the path of movement of said heel presses to permit the heel lifts to be assembled therein, means to drive a building nail thru the lifts while held in assembled position in said form, means whereby the form may be moved to deliver the nailed heels to said presses successively, and means permitting the form to open to permit disengagement thereof from the heel while held by a press.

15. In a heel-building machine, a series of heel presses successively movable to a heel-receiving position, a heel form arranged at one side of the path of movement of said heel presses to permit the heel lifts to be assembled therein, means to drive a building nail thru the lifts while held in assembled position in said form, means to move the form to deliver a nailed heel to each press, successively, while in said receiving position, and means permitting sidewise disengagement of the heel from the form when in said receiving position.

16. In a heel-building machine a series of heel presses successively movable to a heel-receiving position, heel forming means

arranged at one side of the path of movement of said heel presses to permit the heel lifts to be assembled therein, means to drive a building nail thru the lifts while held in assembled position in said forming means, and means whereby said forming means may be moved to deliver a nailed heel to each press, while in said heel-receiving position.

17. In a heel-building machine, a series of heel-presses successively movable to a heel-receiving position, a heel form arranged at one side of the path of movement of said heel presses and having relatively movable heel-forming members, means to lock said members in forming position while the heel lifts are assembled therein, means to drive a building nail thru the lifts while said members are locked, and means whereby said members may be unlocked and the form moved to deliver a nailed heel to each press while in said heel-receiving position.

18. In a heel-building machine, a series of heel presses successively movable to a heel receiving position, a heel form arranged at one side of the path of movement of said heel-presses and comprising a pair of heel forming members, one of said members being movable relatively to the other to and from forming position and means to lock the movable member in forming position while the lifts are assembled in the form, means to drive a building nail through the lifts while the member is locked, means whereby the member may be unlocked and moved to permit sidewise delivery of the nailed heel from the form, and means whereby the other member may be moved, to deliver the nailed heels from the position in which they are assembled to the presses when in heel-receiving position.

In testimony whereof, I have signed my name to this specification.

ARTHUR S. EVERETT.

Witness:

L. H. HARRIMAN.
